Primary Examiner — Anhdao Doan

(74) Attorney, Agent, or Firm — Larson & Larson, P.A.;
Frank Liebenow; Justin P. Miller(57) **CLAIM**

The ornamental design for a device for sunbathing, as shown and described.

DESCRIPTION

FIG. 1 is a perspective view of a device for sunbathing showing my new design;

FIG. 2 is a left side elevation view thereof;

FIG. 3 is a perspective view thereof;

FIG. 4 is a left side elevation view thereof;

FIG. 5 is a right side elevation view thereof;

FIG. 6 is a front elevation view thereof;

FIG. 7 is a rear elevation view thereof;

FIG. 8 is a top plan view thereof; and,

FIG. 9 is a bottom plan view thereof.

The broken lines in FIGS. 1 and 2 represent environmental subject matter and form no part of the claimed design.

1 Claim, 4 Drawing Sheets
